UNITED STATES PATENT OFFICE

93,374

DESIGN FOR A SHOE

Evelyn Ziniti, New York, N. Y., assignor to Scholnick Shoe Co., Jamaica Plain, Mass., a corporation of Massachusetts

Application July 26, 1934, Serial No. 52,691

Term of patent 3½ years

To all whom it may concern:

Be it known that I, EVELYN ZINITI, a citizen of the United States, residing at New York, in the county of New York and State of New York, have invented a new, original, and ornamental Design for a Shoe, of which the following is a specification, reference being had to the accompanying drawing forming a part thereof, in which

The figure is a view in perspective of a shoe showing my new design.

I claim:

The ornamental design for a shoe substantially as shown.

In testimony whereof, I have affixed my signature, reference being had to the accompanying drawing forming a part thereof, in which
